Primary Examiner — Mitchell I. Siegel(74) *Attorney, Agent, or Firm* — Ronald L. Rohde(57) **CLAIM**

The ornamental design for a golf ferrule, as shown and described.

DESCRIPTION

FIG. 1 is perspective view of my new design for a golf ferrule;

FIG. 2 is a front elevation view thereof;

FIG. 3 is a rear elevation view thereof;

FIG. 4 is a top view thereof;

FIG. 5 is a bottom view thereof;

FIG. 6 is a left side elevation view thereof;

FIG. 7 is a right side elevation view thereof; and,

FIG. 8 is a perspective view of FIG. 1 shown with an unclaimed fragmented flag pole inserted.

The portions of the article shown in broken lines represent unclaimed portions of the article and form no part of the claimed design.

1 Claim, 8 Drawing Sheets**FIG. 1**

FIG. 2
